FENCE

Joseph D. Hoffman, Beachwood, Ohio, assignor to Hi-Voltage Equipment Company, Cleveland, Ohio, a division of Joslyn Mfg. and Supply Company, a corporation of Illinois

Application January 27, 1958, Serial No. 49,424

Term of patent 14 years

(Cl. D28—1)

Fig. 1 is a front elevational view of a fence showing my new design, the broken away portions indicating that the fence is of indeterminate length.

Fig. 2 is a sectional view on the line 2—2 of Fig. 1. The rear of each panel element is substantially plain. I claim:

The ornamental design for a fence, as shown and described.
